UNITED STATES PATENT OFFICE.

THEODORE P. LANCASTER, OF BOSTON, AND JAMES L. STRUTHERS, OF LYNN,
MASSACHUSETTS.

ELECTRIC SIGNAL.

1,216,820.

Specification of Letters Patent. Patented Feb. 20, 1917.

Application filed April 29, 1914. Serial No. 835,205.

To all whom it may concern:

Be it known that we, THEODORE P. LANCASTER and JAMES LENOX STRUTHERS, citizens of the United States, residing at Boston, county of Suffolk, and Lynn, in the county of Essex, respectively, and State of Massachusetts, have invented certain new and useful Improvements in Electric Signals; and we do hereby declare the following to be a full, clear, and exact description of the invention, such as will enable others skilled in the art to which it appertains to make and use the same.

This invention relates to electric signals and while the construction is capable of general application, the signal may be employed to advantage as an automobile signal, the object being when so used to give warning of the intended movements of the driver by means of simple signals during the day and by means of signals and lights at night.

With these and other objects in view, the invention consists of the novel construction, combination and arrangement of parts as 25 will be hereinafter described and claimed.

In the drawings wherein similar reference characters designate the corresponding views;

Figure 1 is a rear elevation of an automobile having the invention applied thereto;

Fig. 2 is an end view of the invention;

Fig. 3 is a rear elevation of the indicating or signaling mechanism, the cover as shown in Fig. 2 being removed;

Fig. 4 is a top plan view of the structure seen in Fig. 3;

Fig. 5 is an enlarged vertical section showing the operating mechanism for controlling the signal plates;

Fig. 6 is a diagrammatic view showing the apparatus and wiring therefor.

The general aim of the present invention is to provide within a suitable housing a plurality of pivoted plates actuated by magnetically operated levers so as to be raised into signaling position, the system of levers employed for actuating the plate serving as a support for the plate and also moving so as to prevent any sticking of the plate.

An electric lamp is located adjacent each signaling plate and is placed in a circuit in multiple with the magnet so that said light will become incandescent before the mechanical structure has had time to raise the sig-

naling plate into signaling position, thus 55 producing a flash at the end of the car to attract the attention to those in the rear.

Referring to the drawings 1 designates the base of a frame upon which is mounted the actuating structure for the several signals and there is upstanding from the plate a strut 2 provided with a shoulder 3 upon which rests the bottom of one of the sides of a cover 4. This cover 4 is held to the base 1 by means of screws 5 or any other suitable 60 means and forms a protecting shell for the operating devices and also serves to support lights referred to hereinafter.

Upstanding from one of the long edges of the base 1 are several standards 6 which provide journals in the upper ends thereof for a shaft 7 which runs substantially the full length of the base 1. As shown in Figs. 3 and 4 there are several signals which may be given, a separate actuating device being provided for each signal and a description of any one of these actuating devices will be sufficient for all.

Pivotedly mounted upon the shaft 7 is an arm 8 one end of which extends beneath the shaft 7 and is pivotedly connected to a link 9 which is in turn pivotedly connected to one end 10 of a lever 11. The lever 11 is pivoted as at 12 to a support 13 rigid with the base 1 and the lever 11 has the end 14 thereof pivotedly connected to a link 15 which is pivotedly connected to a plate supporting arm 16. One end of this plate supporting arm is pivoted to the shaft 7 as seen in Fig. 5. Secured to the upper portion of the 90 member 16 is a cushioning device 17 which may be made of cork, rubber or any other suitable material and this cushioning device is to ease the descent of signaling plate 18 which is made rigid with the arm 8 and is 95 located above the arm 16.

In order that the plate supporting arm 16 may be moved to actuate the signal plate 18 there is provided an electromagnet 19 secured to the base 1 and located beneath an armature 20 secured to the under side of arm 16.

From the structure thus far described, it will be understood that as the magnet 19 is energized and attracts the armature 20 the arm 16 will be pulled down to the position shown in dotted lines in Fig. 5 which, of course, results in raising end 10 of lever 11

22
and consequently raising plate 18 to the dotted line position inasmuch as arm 8 which is actuated by link 9 as the lever 11 rotates is rigid with the plate. Should the plate 18 rest upon the cushion or upon the arm 16 so as to become stuck, it will be readily understood that when the magnet is energized there is a tendency to lower the arm and at the same time to raise the plate, there being two opposing motions. This signal plate may be made of any material such as celluloid and has printed thereon either the letter R, S or L as the case may be, these letters standing for the words right, slow and left respectively. We prefer to make the body of the plate black, while the letter is left white, although, of course, any color scheme can be employed.

By referring to Fig. 4, it will be seen that the plate supporting arm 16 is provided with two legs 22 between which the arm 8 may pass when the plate 18 is raised while the forward end is reduced as at 23 to receive the link 15 and also to reduce the weight.

25 By referring to Fig. 2, it will be seen that there is located in the top of the casing 4 an electric lamp 21 which is placed substantially centrally above the signal plate 18 it being understood that there is one of these lamps for each of these plates and in order that the lamp which corresponds to one of the plates may not illuminate adjacent plates, there are provided partitions in the casing 4 shown at 22'. These partitions may 30 extend sufficiently far to shield the mechanism associated with adjacent lights.

By referring to Fig. 6, there will be seen a convenient wiring diagram for actuating the lights and magnets. The battery 24 has extending therefrom a common wire 25 which connects to one side of each of the magnets L, S and R. A three-point switch 26 has contact members l', s' and r' which control the lights l², s² and r² respectively. A 35 three-way switch indicated generally at 27 has three contact members l, s and r which are adapted to engage a contact member 28 which is connected by means of wire 29 to the other side of battery 24. Under ordinary 40 conditions in the daytime when no need of a light is felt, if it is desired to give a signal that an operator is going to the left switch 28 will be thrown to the left to engage the contact member l at which time the following 45 circuit will be closed. Current will flow from battery 24, wire 25, magnet L designating diagrammatically the magnet 19 to the right of Fig. 3, wire 31, contact l, switch 28, wire 29 back to the other side of battery 24, thus energizing the magnet which 50 controls the plate giving the designation corresponding to left. Similarly should switch 28 be thrown to engage the contact member r current would flow in the following circuit: battery 24, wire 25, magnet R designat-

ing diagrammatically the magnet 19 at the left of Fig. 3, wire 33, contact r, switch 28, wire 29 back to battery, thus energizing the plate carrying the designation indicating right. Should it be desired to give a signal to those in the rear that the driver is going to slow up, the switch 28 may be thrown to engage the prong contacts at which time the following circuit will be closed: battery 24, wire 25, magnet S designating the central magnet of Fig. 3 diagrammatically, wire 34, contact s, switch 28, wire 29 back to battery, thus actuating the magnet controlling the plate bearing the designation corresponding to slow.

When the device is to be used at night, the switch 26 may be moved to the dotted line position and the circuit of the light corresponding to the indicating mechanism for signaling left will be given, it being understood that the other circuits are identical with this circuit. Should the switch 28 be thrown to engage contact l after the switch 26 had been thrown in dotted line position, the following circuits will be closed: battery 24, wire 25, magnet L, wire 31, contact l having prongs 30. From wire 25, current will flow over wire 32, lamp l², wire 36, switch contact l' to wire 35, back to contact l, switch 28, wire 29 to battery. From this, it will be understood that the lamp l² and the magnet L are placed in multiple, but it will be understood that before the magnet has had time to actuate the mechanical structure associated with the plate 18, the light l² will be incandescent and will therefore flash up before a driver in the rear and show a bright light before the plate 18 has had time to be raised to signaling position. Current passes from wire 25, through lamp r² or s², point r' or s', and through an insulated portion of switch 26 and thence to contact r or s, whenever switch member 28 is in engagement with either of said contacts last mentioned (switch 26 having first been closed). The handle of switch 26 comprises several portions insulated from each other in order that the lamp circuits may be independent.

The three-point switch indicated generally at 27 may be of any approved construction, and no further description of the same is deemed necessary. This switch may be located at any convenient part of the steering wheel, preferably at the rim and can be operated by one finger.

We claim:

In a signaling device, a plurality of magnets and armatures therefor, a signal operated mechanically by the armature of each magnet, independent circuits for each magnet, a switch having a contact member connected with each circuit, a plurality of lamps corresponding in number with the magnets and having independent circuits, each lamp

circuit having permanent connection with one of the aforesaid contact members of the switch, and a device having a plurality of contact members each connected with a 5 separate lamp circuit and arranged to simultaneously disconnect all of the lamp circuits from the contact members first mentioned.

In testimony whereof we affix our signatures in presence of two witnesses.

THEODORE P. LANCASTER.
JAMES L. STRUTHERS.
